UNITED STATES PATENT OFFICE.

ROBERT C. BRYDEN, OF HAVERHILL, MASSACHUSETTS, ASSIGNOR TO THE SINGER MANUFACTURING COMPANY OF NEW JERSEY.

CLAMP FOR BUTTON-HOLE SEWING-MACHINES.

SPECIFICATION forming part of Letters Patent No. 319,880, dated June 9, 1885.

Application filed February 20, 1885. (No model.)

To all whom it may concern:

Be it known that I, ROBERT C. BRYDEN, a citizen of the United States, residing at Haverhill, in the county of Essex and State of Massachusetts, have invented certain new and useful Improvements in Clamps for Button-Hole Sewing-Machines, of which the following is a specification, reference being had therein to the accompanying drawings.

10 The object of my invention is to add to the convenience of cloth or fabric clamps for button-hole sewing-machines by providing means whereby the spring-depressed guide-pins of such clamps may be quickly and easily lifted from the groove of the feeding-wheel when the button-hole is finished. To effect this result I provide a lifting-lever with which the guide-pin is in engagement, and by which it may be quickly raised when required, said lever being pivoted to an arm or bracket on the guide-pin post.

15 In the drawings, Figure 1 is a plan view of a cloth-clamp embodying my invention, and Fig. 2 is a sectional elevation of the same.

20 A indicates the base-plate by which the clamping-jaws are carried, and B is a hollow post attached thereto, through which post the guide pin C passes. The post B has an arm or bracket, b, to which is pivoted the lifting-lever D, and to the top of said bracket is attached a spring, E, the free end of which is 25 in engagement with the pin C, the said spring

serving to depress the said pin, and the latter being preferably provided with a flange, c, or other projection, near its top, beneath which 35 the top or forward end of the lever D extends.

The post B is provided at its top with a notch in which the lifting end or toe of the lever D fits, said lever, when not in use, being held in place between the bottom wall of said 40 notch and the flange c. A stop-pin, b', serves to limit the lifting movement of the lever D.

By depressing the rear end of the lever D the guide-pin C may be quickly and easily lifted, thus obviating the inconvenience incidental to the clamps heretofore in use, in which the guide-pins are lifted by pulling upward on their heads.

I claim as my invention—

In a button-hole clamp, the combination, 50 with the base-plate, of a hollow post having a notch at its top and an arm or bracket, a guide-pin fitting in said post and having a flange or projection, a lifting-lever pivoted to said bracket and extending into said notch 55 beneath said flange or projection, and a spring for depressing said pin, substantially as set forth.

In testimony whereof I affix my signature in presence of two witnesses.

ROBERT C. BRYDEN.
